Attorney.

UNITED STATES PATENT OFFICE.

WALTER G. LAIDLAW, OF SYRACUSE, NEW YORK, ASSIGNOR TO KLEEN KAP CORPORATION, OF SYRACUSE, NEW YORK, A CORPORATION OF NEW YORK.

BOTTLE CLOSURE.

Application filed October 15, 1926. Serial No. 141,834.

This invention relates to improvements in bottle closures, and has for its object to provide a unitary disc-shaped closure, which is formed with a foldable tab for removing 5 the disc from the bottle mouth without danger of destroying the said tab or distorting the closure. And a further object is to provide novel means controlled by the said tab for extracting the contents from the bottle 10 by the use of straws and the like, without disturbing or removing the closure.

I attain these objects by the means set forth in the detailed description which follows, and as illustrated by the accompanying 15 drawing, in which—

Figure 1 is a broken central vertical section, showing the closure applied to the mouth of a bottle; also showing by full and dotted lines the arrangement and operation 20 of the closure-removing tab. Fig. 2 is a broken plan view of a strip of material from which the closures are cut; showing the strip operated upon for forming the tab. Fig. 3 is a top plan view of the closure; showing the 25 tab and the corresponding portion of the disc reduced in thickness. Fig. 4 is an edge view of the closure when first stamped from the strip of material. Fig. 5 is an edge view, showing the closure bent for facilitating 30 splitting and removing the top layer of the tab. Fig. 6 is a broken edge view, showing the disc straightened and the tab and disc perforated. Fig. 7 is a similar view, showing the tab folded upon the recessed portion 35 of the disc. And Fig. 8 is a top plan view of the closure ready to be applied to a bottle.

In the drawing, 2 represents an ordinary milk bottle, having a neck 2', which is surrounded by a bead 3, the latter encircling 40 the usual sunken mouth 4, whose bottom comprises an annular ledge 5, upon which the well-known disc closure, as 6, rests for sealing the bottle mouth.

My closure comprises a single disc-shaped 45 part, preferably stamped out of a continuous strip, as 6', of card-board, pulp-board, or the like, of suitable thickness and stiffness, to properly close and seal the mouth 4. To afford convenient means for readily and 50 quickly removing the disc 6, without injuring or distorting the disc, I provide an integral tab or ear, as 7, which preferably extends beyond the periphery of the disc, when the parts are first formed; the said tab also 55 preferably being disposed at an angle to the

linear dimension of the strip 6', so as to facilitate stamping the discs with as little waste of the material as possible. In forming the tab 7, the strip 6' is preferably passed between suitable feed rolls (not shown), to a certain position and stopped long enough for a die, or other instrument, preferably oval in shape (not shown), to cut through the web of the strip, for forming the tab portion that extends beyond the periphery of the disc, and at the same time, the same die preferably cuts or scores the adjacent top surface or portion of the disc, as at 7' (see Fig. 2), to the extent of about one-half the thickness of the web. The strip 6' may then be operated upon 60 by another die (not shown), for cutting the disc from the strip, as shown in Fig. 4, after which the disc is preferably bent, substantially at 7^a, so as to incline the tab and the adjacent portion of the disc, as shown at x 65 in Fig. 5. This bending of the disc tends to split the card-board in the plane of the bottom of the scoring 7', as shown at 7^a, in Fig. 5. The operator, or a suitable knife (not shown) carried by the machine, next 70 peels or shaves off the upper half of the tab and the correspondingly shaped portion of the disc enclosed by the scoring 7', for forming a recess 6^b, after which the disc is restored to its plane state, as shown in Fig. 6. 75 This reducing of the tab 7 renders it sufficiently pliable to be readily folded and unfolded during the operation of the closure. The next step in the manufacture of the closure consists of punching a hole, as 6^c (see 80 Figs. 3, 6, 7 and 8) in the bottom of the recess 6^b, and at the same time punching a narrow slot 7^b at the base of the tab 7, for facilitating the folding of the tab without 85 distorting the periphery of the disc or destroying the tab. The final operation consists of folding the tab 7 inwardly upon the disc and pressing the tab into the recess 6^b, as shown in Figs. 1, 7 and 8. When the tab 90 95 95 100 105 110 115 116 117 118 119 120 121 122 123 124 125 126 127 128 129 130 131 132 133 134 135 136 137 138 139 140 141 142 143 144 145 146 147 148 149 150 151 152 153 154 155 viates the danger of dirt or germs entering the bottle either before or during the withdrawing of the contents. The drawing off of the contents of the bottle by means of a straw may be effected in one or in several operations, and in the intervals between said operations, the tab 7 may be depressed for closing the recess and also the perforation 6^a, as shown in Figs. 1, 7 and 8. By providing the relatively thin tab 7, as herein shown, the tab may be readily folded upon the disc and fitted snugly into the recess 6^b, where it will remain until lifted by one's finger nails, or by the use of any suitable instrument, and when the tab is lifted, as shown in Fig. 1, a slight pull in the linear direction of the tab will readily unseat and lift the disc, without danger of tearing or otherwise injuring the tab. By providing the small slot 7^b, as herein shown, the tab may be folded upon the disc without danger of breaking the grain of the paper, and when the said slot is properly positioned, the periphery of the disc at its intersection with the tab retains its normal curvature instead of being flattened at said point, as heretofore.

Having thus described my invention, what I claim is—

1. A bottle closure comprising a fibrous disk having an integral radial tab projecting outwardly from its periphery, said tab being

of reduced thickness relative to the thickness of the disk and the upper face of the latter adjacent the tab being formed with a depression, the upper face of the depression forming a continuation of the upper face of the tab when the latter is extended, the tab being folded along a line substantially in register with the adjacent peripheral part of the disk and engaging in the depression so as to extend flush with the upper face of the disk. 35

2. A bottle closure comprising a fibrous disk having an integral radial tab projecting outwardly from its periphery, said tab being of reduced thickness relative to the thickness of the disk and the upper face of the latter adjacent the tab being formed with a depression, the upper face of the depression forming a continuation of the upper face of the tab when the latter is extended, the tab being formed with a transverse slot aligned with the periphery of the disk and being folded along the slot and engaging in the depression so as to lie flush with the upper face of the disk, the bottom wall of the depression being formed with an opening to enable the bottle contents to be removed without disturbing the disk. 45 50 55

In testimony whereof I affix my signature.

WALTER G. LAIDLAW.
